UNITED STATES PATENT OFFICE

GEORGE DECKER, OF CLEVELAND, OHIO, ASSIGNOR TO THE PHILAD COMPANY, OF CLEVELAND, OHIO, A CORPORATION OF OHIO

APPARATUS FOR HAIR WAVING

Application filed November 4, 1929. Serial No. 404,644.

This invention relates to apparatus for waving hair upon the human head and more particularly to apparatus which will both retain the hair in coiled position while the same is being subjected to a waving process and also supply the heat necessary in the performance of this process.

An object of the invention is to provide an improved apparatus which will eliminate the necessity for separate heaters and head protecting devices which has existed heretofore in the "permanent" waving of hair.

Another object is to provide an improved apparatus which may be conveniently operated.

Other objects will hereinafter appear.

The invention will be better understood from the description of one practical embodiment thereof illustrated in the accompanying drawing, in which:

Figure 1 is a perspective view of the apparatus with parts in the positions they occupy before being applied to a strand of hair;

Figure 2 is a cross-sectional view of the parts of Figure 1 taken on the line II—II of Figure 1;

Figure 3 is a side elevational view of the apparatus of Figure 1 together with the curler rod upon which a strand of hair is wound, showing the position these parts occupy during the waving process;

Figure 4 is an end view of the apparatus of Figure 3 taken from the left;

Figure 5 is a transverse sectional view of the apparatus of Figure 3 taken on the line V—V thereof;

Figure 6 is an end elevation of the apparatus of Figure 3 taken from the right; and

Figure 7 is a longitudinal sectional view taken on the line VII—VII of Figure 4.

The apparatus shown consists of a clamp or protector having two arms 1 and 2 for engaging a flat strand of hair adjacent the scalp of the wearer, one of the arms being provided with means for supplying heat requisite in giving the strand a wave. Each of the arms consists of a channel-shaped metal bar 3 to the under-surface of which is secured a coextensive bar of heat insulating material such as balsa wood. One end of each bar is

pivotedly connected by rivet 5 to a pair of superposed links 6 so that the two arms may swing relative each other. The arm 1 has pivoted to its free end, by a rivet 7, two links 8 arranged to embrace the free end of arm 2, 55 a latching member 9 being pivotally connected by a rivet 10 to the other ends of the links 8.

Carried by the first mentioned end of arm 1 is a spring 11 provided with a detent 12 for 60 engaging the end of a curler rod on which the strand of hair is wound and retaining this rod against rotation in one direction so that the hair cannot become upwound during treatment.

The opposed open sides of the channel members 3 have shallower channel members 13 secured therein, the latter being provided with strips 14 of rubber or other resilient material to grip the strand of hair. The parts so far described are similar to those shown in my copending application Serial Number 379,187, filed July 18, 1929. 70

Carried by the arm 1 is a casing 15 in which is pivotally mounted a roller 16 carried by trunnions 17 attached to the casing and surrounding a helical spring 18, one end of which is connected to one of the trunnions and the other end of which is connected to the roller to rotate the same in a counter-clockwise 80 direction when the parts are in the positions shown in Figures 2, 5 or 6. Carried by this roller is a curtain 19 of asbestos fabric or other suitable flexible fireproof material in which is woven a quantity of resistance wire 85 which constitutes a heating element and is connected to lead-in wires 20 by which current may be supplied. The outer edge of this curtain is provided with a rod 21 slightly longer than casing 15 so that it cannot pass 90 into the interior thereof, the projecting ends of the rod being arranged to be inserted beneath the lugs 22 struck up from the surface of channel 3 of arm 2.

The operation of the apparatus is as follows:—The hair on the subject's head is divided into a plurality of flat strands and one strand is engaged adjacent its roots between the arms 1 and 2, these being clamped together by the latch 9. This strand is then 100

wound from its ends about the curler rod 23 which consists of a tubular member provided at one end with a plurality of longitudinally extending slots 24. This rod is rotated to wind the strand spirally thereon, one turn over another, until it lies upon the arm 2, bearing against casing 15, the slotted end of the rod being in contact with spring 11, the detent 12 of which may engage one of the slots 24. The slots and spring act as a ratchet and pawl so that the rod may be further rotated to maintain the hair under tension and will be prevented from rotating in a direction to loosen the hair.

15 The wound strand of hair, treated with any desired solution and if desired enclosed within a pad or flannel containing solution, is covered by the curtain by simply drawing this forth from the casing, slipping the ends 20 of rod 21 under the lugs 22, after which the current may be supplied to the heating element in the curtain for the time necessary to effect the desired wave. When the heating has been completed it is only necessary 25 to disengage the ends of rod 21 from the lugs, whereupon the spring and roller will retract the curtain into the casing, after which the curler rod and protector may be removed in the customary manner.

30 While I have described the illustrated embodiment of my invention in some particularity, obviously many others will readily occur to those skilled in this art, and I therefore do not limit myself to the precise details shown 35 and described, but claim as my invention all variations, modifications and embodiments coming within the scope of the subjoined claims.

I claim:

- 40 1. Hair waving apparatus comprising a protector clamp having two elongated arms between which a strand of hair may be gripped, a curler rod on which the strand may be wound, retaining means for holding the 45 rod upon the clamp, and a heater permanently attached to the clamp and movable so that in one position it will overlie the coiled strand.
2. Hair waving apparatus comprising a protector clamp having two elongated arms 50 between which a strand of hair may be gripped, a curler rod upon which a strand of hair may be wound, ratchet means carried by said clamp and rod to prevent rotation of the rod with respect to the clamp in one 55 direction, and a heater permanently carried by said clamp and movable into a plurality of positions in one of which it overlies the wound strand.
3. Hair waving apparatus comprising a 60 protector clamp having two elongated arms arranged to grip a strand of hair between them, a curler rod upon which the strand of hair may be wound and arranged to lie upon the clamp, means for preventing rotation of 65 the rod in one direction, a casing carried by

one of the arms of the clamp, an extensible curtain normally housed within said casing and arranged to overlie the wound strand of hair, and heating means associated with the chamber formed by the protector clamp, the casing, and the curtain.

4. Hair waving apparatus comprising a protector clamp having two elongated arms arranged to grip a strand of hair between them, a curler rod upon which the strand of hair may be wound and arranged to lie upon the clamp, means for preventing rotation of the rod in one direction, a casing carried by one of the arms of the clamp, an extensible curtain normally housed within said casing and arranged to overlie the wound strand of hair, and a heating element carried by said curtain.

5. Hair waving apparatus comprising a protector clamp having two elongated arms arranged to grip a strand of hair between them, a curler rod upon which the strand of hair may be wound and arranged to lie upon the clamp, means for preventing rotation of the rod in one direction, a casing carried by one of the arms of the clamp, a roller carried within said casing upon which a curtain may be rolled, a spring for rotating the roller in a direction to retract the said curtain into the housing, an extensible curtain connected to the roller and normally housed within said casing and arranged to overlie the wound strand of hair, and heating means associated with the chamber formed by the protector clamp, the casing, and the curtain.

6. Hair waving apparatus comprising a protector clamp having two elongated arms arranged to grip a strand of hair between them, a curler rod upon which the strand of hair may be wound and arranged to lie upon the clamp, means for preventing rotation of the rod in one direction, a casing carried by one of the arms of the clamp, a roller carried within said casing upon which a curtain may be rolled, a spring for rotating the roller in a direction to retract the said curtain into the housing, an extensible curtain connected to the roller and normally housed within said casing and arranged to overlie the wound strand of hair, heating means associated with the chamber formed by the protector clamp, the casing, and the curtain, and engageable securing means carried by the edge of the curtain and the other arm of the protector clamp.

7. Hair waving apparatus comprising a protector clamp, a curler rod upon which a strand of hair may be wound and adapted to be positioned upon the clamp, a flexible curtain movable to overlie the wound strand of hair, and a heating element in said curtain.

8. Hair waving apparatus comprising a protector clamp, a curler rod upon which a strand of hair may be wound and adapted to be positioned upon the clamp, a flexible cur-

12

130

tain movable to overlie the wound strand of hair, and a resistance wire woven into said curtain and constituting a heating element for heating said strand of hair.

5 9. Hair waving apparatus comprising a protector clamp having two elongated arms arranged to grip a strand of hair between them, a curler rod upon which the strand of hair may be wound and arranged to lie upon the clamp, means for preventing rotation of the rod in one direction, a casing carried by one of the arms of the clamp, a flexible curtain normally housed within said casing and arranged to overlie the wound strand of hair, 10 resistance wire woven into said curtain, and means for connecting said wire to a source of electrical current so that heat may be supplied to the strand of hair.

15 10. Hair waving apparatus comprising a protector clamp having two elongated arms arranged to grip a strand of hair between them, a curler rod on which the strand of hair may be wound and arranged to lie upon the clamp, means preventing rotation of the rod 20 in one direction, a casing carried by one of the arms of the clamp, a roller within said casing, a flexible curtain normally rolled upon said roller, a spring for rotating the roller in a direction to retract the curtain into the 25 housing, the curtain in extended position 30 overlying the wound strand of hair, and resistance wire woven into said curtain to constitute a heating element for the chamber formed by the protector, casing, and curtain.

35 In testimony whereof I hereunto affix my signature this 29th day of October, 1929.

GEORGE DECKER.
